CONTROL MECHANISM FOR PRESSING MACHINES

Otto H. Pearson, Salt Lake City, Utah, assignor to L. N. Strike, Salt Lake City, Utah

Application September 16, 1940, Serial No. 356,931

8 Claims. (Cl. 192—131)

My invention relates to laundry presses and has for its object to provide a new and highly efficient two hand controlled laundry press which is positive and sure in its action, which locks the movable buck in the closed position until released manually or automatically and which incorporates many new and improved features never before found in such types of presses.

A further object is to provide a laundry press using five like valves to control the press, two of which are used and must be used by the operator to bring the movable head into contact with the stationary buck, two of which are used either together or independently to release the movable head, and the other which controls the operating cylinder after the first two have been operated by the operator, all of the valves being identical in form the only difference being that the size of some may be larger than others if desired or required to control the fluid pressure for operating the head.

A still further object is to provide a new system of controlling the movable head in which a two-hand control system is combined with a diaphragm to operate an over-center toggle operating the master valve and the press and to release the press by operating the toggle in the opposite direction by a diaphragm with means in the path of travel of the toggle to hold it from passing over center until the movable head has engaged the stationary buck or to approximate contact with the buck depending upon the adjustment of the leverage.

A still further object is to provide a two hand control for pressing machines which when actuated operate a diaphragm to shift a toggle, to operate a master valve, close the movable head; with the toggle held from passing over dead center until the operating machine of the press has reached a predetermined position at which time a barrier is removed from the path of the toggle and the head is locked in closed position.

A still further object is to provide a two hand controlled pressing machine having a single toggle to control the master valve with a withdrawable barrier in the path of travel of the single toggle to prevent it passing over dead center until the barrier has been removed by pneumatic and mechanical means.

A still further object is to provide a device as set out in the above objects in combination with an automatic release actuated by and due to the wear of the padding on the press and which will release the press by the tilting of the power cylinder or other means which will release a con-

trol toggle by the action of the lever which controls the barrier again throwing the toggle back to original position by the relative position of the lever and the relative position of the power cylinder.

A still further object is to provide an automatic time control mechanism which will hold the movable head in contact with the stationary buck a predetermined period of time and then by the flow of mercury or fluid through a constricted orifice will release the movable head.

A still further object is to provide a control for presses which when the head engages the buck or near it it releases air from the manual valves and no pressure is in the lines or valves due to operation of master valve, thus eliminating the need of means to hold manual valves.

In the drawings,

Figure 1 is a diagrammatic vertical section of a press, parts shown in elevation, showing how my controls are mounted.

Figure 2 is a side elevation of a small type press, parts shown cut away, to show the operating mechanism.

Figure 3 is a diametrical section of the master valve.

Figure 4 is a diagrammatic view of the control system for the press showing the method of operating the toggle control for the master valve.

Figure 5 is a side elevation of the automatic timer device.

Figure 6 is a diagrammatic view of the control system used with the timer for automatically timing the period for holding the movable head engaging the pressing buck.

Figure 7 is a diametrical section of the mercury or fluid timer cylinder.

Figure 8 is a diametrical section of the control valve used in the timer.

In the drawings, I have shown my press with a movable pressing head A, and stationary buck B. The buck B is mounted on a framework C and the movable head is mounted on one end of a pivotally mounted pressing arm D. A toggle E operates the arm D and head A and a power cylinder F provides the power for the press.

The cylinder F is pivoted at one end by a pivot 4 and is provided with a piston 5 on the end of a piston rod 6. The outer end of the rod 6 is attached to a leg 7 of a crank member 8 which in turn is attached to the toggle E at the junction of the lower arm 9 and upper arm 10. A set of rollers 11 is mounted on the end of the rod 6 adapted to roll up an inclined cam 12, the top of the cam being arc-shaped at 13 with

the rollers adapted to follow the face of the cam incline 12 and then descend on the arc 13 for final pressure, the coacting high pressure being applied by the form of the crank member 8 which is not a part of this invention having been covered in former copending patent applications, filed by myself and associated under Serial No. 162,620, filed Sept. 7, 1937, for Toggle mechanism for presses.

Mounted at the front of the table H of the press are my control members. These consist of spaced manual buttons 15 and 16 for actuating the press and lesser spaced release buttons 17 and 18. These buttons are set above pivoted levers L all of which are alike and occur under all of the finger tip control buttons. The ease which this press is operated is due to the controls thereof. The levers L are pivoted in suitable brackets 19 attached to the underside of the table H and in alignment with each lever there is one of my control valves. These valves are alike in form and shape the only difference being in their sizes and as they are all alike I will describe the master valve which is also like these valves, hereafter in this application.

These valves will for clarity be each given a different number and each performs its required function. The two outer valves or control valves 21 and 22 are attached in series. A pipe 23 leads fluid or air pressure from a source of supply (not shown) into the first valve 21 and through the ports of the valve when actuated by the finger of the operator through the pipe 24 to the next valve 22. From the valve 22 another pipe 25 leads to a toggle operating diaphragm 26. These two valves are so hooked up that when the valve 21 is pressed the pressure will pass through the valve to the next valve 22 but unless the second valve 22 is pressed the air stops there. If the second valve is depressed simultaneously with the first then the air actuates the diaphragm 26, operating the toggle lever 50 when the barrier is removed. This is fully described hereinafter. The air from the pipe line 23 also leads to the master valve V. This valve is mounted through the flanged end of a mounting plate 28 secured onto the top side of the power cylinder F. The valve as shown in Figure 3 is made of a casing 29 having a longitudinal bore therethrough having many diameters. A closure plug 27 is fitted into the end which is termed the pressure end in which the pipe line 23 is connected in the threaded hole 30. A chamber 32 is formed in this end of the cylinder by a valve seat partition 31. The chamber on the other side of the valve partition shown as chamber 33 is in open connection with a port 34 which leads through a short nipple into the interior of the power cylinder F.

The chamber 33 merges into a larger diametered exhaust chamber 34 in which an exhaust port 35 is bored to discharge air from the cylinder after each operation thereof. In the end of this chamber 34 there is a threaded guide plug 37 through which an actuating rod 38 is passed. This rod 38 carries a spring held ball 38a in the end thereof to take up wear of the valves. The valve in the chamber 32 for controlling the pressure from the source of power is provided with an extended stem 39 fitting into a socket 40 in the plug 37 and the valve 41 is of larger diameter than the stem and normally is held seated against the valve seat partition 31 by a spring 42. A stem 43 extends on the other side of the valve 41 into the chamber 33. The other valve 45 is of larger diameter and fits against the seat formed by the

step of the larger diameter chamber to the smaller diameter chamber 33. This valve 45 has one end formed as a small stem 46 to engage the stem 43 and open the valve 41 from the seat 31. The opposite side of the valve 45 is formed as a guide stem 47 fitting into the bore of the plug 38. This larger stem is engaged by the rod 38.

A three section toggle T is mounted so that one arm 48 engages the ball 38a to actuate the valve assembly when shifted by the movement of the other two arms 49 and 50. The three arms are pivotally attached to each other and one end of the arm 48 is pivotally attached to the plate 28 by a pivot 51. The other outer arm of the toggle 50 is attached to the plate 28 by a pivot 52 thus the central section of the toggle is attached to the other two members but is free to move. The toggle arm 50 is mounted near the actuating arm 53 of the diaphragm 26 thus when the diaphragm is actuated the toggle is actuated.

A stop or barrier for the toggle is provided to keep it from passing over dead center until desired and consists of a vertically partially rotatably mounted rod crank 54 mounted in a cylinder base 55 which attaches to the plate 28. A ball 56 is carried in a recess in the base with one side of the ball extending to be engaged by the toggle arm 53 and prevent it moving farther until the crank rod 54 has been partially rotated. A recess is formed in the rod 54 into which the ball 56 recedes when the rod has been partially rotated withdrawing the ball sufficiently for the toggle to pass over dead center. When this happens the pressing head is held in pressing relationship with the buck until released by reverse action of the toggle. This is accomplished primarily by a diaphragm 58 mounted on the opposite side of the plate 28 with the shaft 59 of the diaphragm adapted to press against the central toggle arm 49. A pipe 60 leads to this diaphragm from a check valve coupling 61 which is connected by two pipes 62 and 63. The pipe 62 leads to one release valve 64 and the pipe 63 leads to the release valve 65. These are the two release valves controlled by the finger controlled release buttons 17 and 18, and levers L are mounted behind and under these buttons similar to the way the other valves are mounted to be actuated by the buttons 15 and 16 and the control levers L. When the release valves 64 and 65 are operated the air passing through pipes 62, 63, and 60 actuates the diaphragm 58 which in turn moves the toggle T by the shaft 59 pressing against the lever 49. The movement of the toggle T over center caused by the pressure of the shaft 59 releases the valve V and thereby releasing the press.

A pipe 67 connects the valve 64 with the source of fluid pressure through a coupling on the top of the valve 21 and this source of power is also connected to the valve 65 so that both valves are provided with air pressure or fluid pressure. Thus in the hook up shown in Figure 4 the release valves may either one be utilized for releasing the press but in Figure 6 the valve 65 is shown as for tandem purposes or in other words to release the next in a series of presses used in a semi-circle around the operator.

The rotatable crank rod 54 has the crank end thereof attached to the framework by an adjustable link 54a so that any movement or oscillation of the power cylinder caused by the rollers passing up the incline 12 will change the relative position of the crank rod 54 which is the means for permitting the toggle to pass beyond

dead center and the relative movement of the cylinder F controls the relative position of the crank rod. Should the padding become worn, so that the press when operating comes down too far, the rollers 11 passing over the arc 13 will travel too far which reverses the action of the crank rod 54 causing the ball 56 to engage the lever arm 50 of the toggle instantly releasing the press by forcing the toggle back beyond dead center to its initial position exhausting the pressure from the cylinder F by releasing the master valve V.

The adjustment of the link 54a and of the arm 10 of the toggle E control the position when this action takes place.

To control the pressing head and automatically time the period for pressing I have provided a timer which shown in Figures 5 to 8, inclusive, regulates to any predetermined period the time for holding the head engaged with the buck.

The timer consists of an angle bracket 61a which is attached to the framework C of the machine and which bracket carries an extended L to the end of which a pressure diaphragm is mounted. This diaphragm 68 is connected to the diaphragm 26 by a pipe 71. A cylinder 73 is mounted to the base of the bracket 61a and carries a piston 74 which piston is provided with ports 75 and vent control nut 76 with the head of the cylinder closed and a plug is screwed into the open end of the cylinder with the piston rod 77 passing through the plug to engage an actuating lever 78. The piston is filled with mercury or other suitable fluid and the time required for the fluid to pass through the ports controls the speed of drop of the piston. The end of the lever 78 is turned down and engaged by the rod of the diaphragm 68. The lever is pivoted at 79 for fulcrum pivot and pressure by the diaphragm raises the outer longer end of the lever raising the piston in the mercury. A spring 80 is mounted adjustably to the end of the lever 78 with the tension of the spring pulling the end of the piston downwardly causing the piston to settle through the mercury as the tension of the spring pulls it and the speed of lowering of the outer end of the lever is governed by the tension of the spring and the size of the ports in the piston.

A valve 81 is mounted to the bracket 67 and the stem 82 of the valve 83 is engaged by an adjustable bolt 84 mounted through the lever 78 when it reaches a predetermined position and the position is adjusted by the predetermined time required or desired for holding the press closed. The valve may be of a type such as shown in Figure 3 or may be as shown in Figure 8 with a ball valve 85 held to its seat 86 by a spring 87. The stem 82 of the valve 83 passes out through the plug 88 and the seat 89 of the ball valve is so made that when the valve is pressed away from the seat pressure will pass from one side to the other. A pipe 90 is connected in the port 91 in the master valve V by removing the plug 92 and inserting the end of the pipe into the threaded end of the port, and the pipe leads into the lower chamber 93 of the valve 81. The chamber above the valve seat is then connected through the check valve to the diaphragm 58 by a pipe 94.

Having thus described my invention, I desire to secure by Letters Patent and claim:

1. A control for power cylinders of laundry presses comprising, spaced control valves in series adapted to be manually actuated; a source of fluid pressure; a diaphragm connected with said valves, said diaphragm to be actuated when both valves are operated simultaneously; a toggle mounted adjacent the diaphragm to be actuated thereby; a master valve mounted to be actuated by said toggle to control the power cylinder to close the press and after the press has been actuated the valves are open and free from fluid pressure.
2. A device as set out in claim 1 including means to release said press by spaced release valves either of which may be operated and a fluid means diaphragm to return the toggle to the initial position.
3. A device as set out in claim 1 including, a lever connected to the power cylinder having a recess therein adapted to permit a barrier to fit into said recess to permit the toggle to move to its over center position when the power cylinder has been moved a predetermined distance by the operating mechanism of the press.
4. A control for the power cylinders of laundry presses comprising, a master valve mounted to direct air into said cylinder; means to connect with the cylinder to move a movable head to engage a stationary buck; a three armed pivotally connected toggle mounted to have one arm thereof engage and actuate the master valve; a diaphragm mounted adjacent said toggle to actuate the toggle and thereby the master valve; spaced manually controlled valves to be simultaneously engaged to actuate said diaphragm and thereby actuate the toggle, the master valve, and cylinder in turn, causing the movable head of the press to close to the stationary buck; and a diaphragm mounted adjacent said toggle to shift in the opposite direction to release the master valve and thereby the press.
5. A device as set out in claim 4 including, a lever mounted on the power cylinder with one end connected with the framework of the press; and a barrier ball controlled by said lever said ball to be directly in the path of the toggle when the toggle has first been operated but to be withdrawn from the path of travel when the cylinder has been moved to a predetermined position.
6. A control for presses comprising, spaced manually controlled valves; a master valve; a diaphragm operated by the spaced manually controlled valves and connected with toggle means to operate said master valve, said manual valves having no pressure therein after the master valve has been actuated.
7. A device as set out in claim 1 including, means to release said press by spaced manual release valves either of which may be operated and fluid means to return the toggle to the initial position.
8. A device as set out in claim 6 including, an automatic fluid timer to release the press after a predetermined period.

OTTO H. PEARSON.
